(57) **CLAIM**

The ornamental design for the ultrasonic wound treatment probe, as shown and described.

DESCRIPTION

FIG. 1 is a top, front, and left side perspective view of an ultrasonic wound treatment probe, showing our new design;

FIG. 2 is a bottom plan view thereof;

FIG. 3 is a front elevational view thereof;

FIG. 4 is a top plan view thereof;

FIG. 5 is a rear elevational view thereof;

FIG. 6 is a left side elevational view thereof, the right side elevational view being identical thereto; and,

FIG. 7 is a longitudinal and axial cross-sectional view, taken perpendicular to the plane of the drawing in FIG. 4.
